UNITED STATES PATENT OFFICE

WILLIAM CAMERON, OF CHICAGO, ILLINOIS, ASSIGNOR TO CAMERON CAN MACHINERY COMPANY, OF CHICAGO, ILLINOIS, A CORPORATION OF ILLINOIS

STOP MECHANISM FOR PRESSES

Application filed September 15, 1928. Serial No. 306,255.

This invention relates to die presses in general and more particularly to a mechanism for automatically stopping the same when more than one or an excessively thick blank 5 is fed between the dies.

Mechanisms have been used heretofore in connection with die presses for automatically stopping the press or the machine when an excessively thick or more than one blank is being fed. These mechanisms operate with varying degrees of accuracy and reliability and are usually disposed in proximity to the feedway and spaced from the dies. Should these mechanisms fail, there would be nothing to prevent an excessively thick or more than one blank being delivered between the dies. The primary object of this invention is accordingly to provide a mechanism for automatically stopping the press when an excessively thick or more than one blank is fed between the dies. This mechanism may be used without the above mentioned automatic stop mechanisms or it may be used in conjunction therewith as an added safety device 25 or auxiliary mechanism.

Other and further objects of this invention will become apparent as the same becomes better understood from an examination of the specification and claims in connection 30 with the accompanying drawings wherein

Fig. 1 is a side elevation partly in section and with the parts cut away of an automatic die press of the type illustrated and described in connection with my prior Patent #1,477, 35 240 of December 11, 1923.

Fig. 2 is a fragmentary view of the press taken at the line 2—2 of Figure 1 illustrating the parts in normal running position.

Fig. 3 is a similar fragmentary view illustrating the parts in position upon the occurrence of a blank of abnormal thickness.

Fig. 4 is an enlarged detailed view showing part of the mechanism removed.

Fig. 5 is an enlarged detailed plan view of another part of the mechanism.

Fig. 6 is an elevation of the part shown in Fig. 5.

Fig. 7 is a section taken at the line 7—7 of 50 Fig. 5.

Fig. 8 is a section taken at the line 8—8 of Fig. 5.

Referring to the drawings more particularly, the reference character 9 represents a frame provided near its top with suitable bearings 11 in which the main power shaft 12 of the die press is journaled. The shaft 12 is suitably driven and provided with a fly wheel or a belt pulley 13, and a central crank 14 between the spaced bearings 11, by means of which a cross head 15 is reciprocated in the guideway 16 of the machine frame to reciprocate the upper die 17 to co-operate with the stationary lower die 18 mounted on the bed of the machine. The blanks of tin or other material to be operated upon are adapted to be disposed in a pile in the magazine (not shown) from which they are to be lifted in succession by a series of suction cups (not shown) into alignment with the feed channel, whereupon they are moved laterally edgewise into this channel by a suitable transferring device. The blanks are then fed along the channel to the dies 17 and 18 one at a time by a feed slide 19, which is provided with a series of dogs 21. The operation of the aforementioned parts will be clearly understood from an examination of my aforesaid prior Patent #1,477,240, and my prior Patent #1,277,342, of August 27, 1918.

Should more than one or an excessively thick blank be fed between the dies 17 and 18, the shaft 12 will be caused to spring as the same is rotated, and the dies 17 and 18 come together on such abnormal number of blanks or excessively thick blank. The amount that the shaft 12 is thus caused to spring is ordinarily very small for a blank of slightly abnormal thickness, but it is sufficient to effect the operation of the automatic stop mechanism hereinafter described.

A laterally projecting lug 22 is provided on the wheel 13 near its outer periphery. This lug is given a lateral movement upon the temporary distortion of the shaft 12 by the abnormal blank or number of blanks between the dies, and this movement is appreciable by reason of the spaced position of the wheel 13 from the crank 14, and also by reason of said

lug being positioned so far out on the radius of said wheel.

Normally this lug 22 is carried by the wheel 13 out of contact with the mechanism adapted to be actuated by said lug, to cause the stopping of the press, but when this lug is given the lateral movement just described, it engages said mechanism which will presently be described.

10 A hand lever 23 is fixedly mounted on a shaft 24 and has an extension 25 pivotally connected with a link 26. This link is adjustably connected to a rod 27, which in turn is connected to a clutch shoe 28 for stopping the 15 press. These parts 23 to 28, inclusive, whereby the handle may stop or start the press are substantially the same as shown in my prior Patent #1,477,240, above mentioned.

16 A laterally extending arm 29 is pivotally mounted on a pin 31 carried by a bracket 32, which is bolted to the frame at the side of the guideway 16. This arm 29 is provided with a renewable projection 33, at its outer end, adapted to be engaged by the lug 22 20 as the same is rotated and given its lateral movement previously described. When the lug 22 engages the projection 33, the arm 29 will be actuated downwardly. The arm 29 is apertured to receive the upper end of a rod 34 and is adjustably connected therewith by 25 means of nuts 35.

26 The lower end of the rod 34 is pivotally connected to a lever 36. The lever 36 is pivotally mounted on a pivot 37 in the form of a 30 bolt attached to the frame of the machine in proximity to a guideway 38 also attached to said frame. The outer end of the lever 36 is provided with a handle 39, whereby the lever may be manually actuated as well as automatically by the rod 34 when the arm 29 is actuated by the lug 22 as previously described. The inner end of the lever 36 is in 35 the form of a projection or stop 41, which normally extends into the guideway 38 in engagement with a shoulder 42 on a slide 43 in 40 said guideway. A spring 44 normally holds the lever 36 in position to cause the stop 41 to engage the shoulder 42 and is adapted to yield under action of the rod 34 and arm 29 45 when the same is actuated.

46 A link 45 is pivotally connected at one end to the slide 43 and at its other end to the extension 25 whereby action of the slide in one direction may cause parts 23 to 28, inclusive, 50 previously described to be actuated for stopping the press. A spring 46 secured at one end to the link 45 and at the other end to the frame tends to move the slide to cause it to 55 actuate the said mechanism comprising parts 23 to 28, inclusive, for stopping the press, but so long as the stop 41 is in engagement with the shoulder 42, this is prevented.

56 In operation upon the occurrence of a blank of abnormal thickness the movable die will not be able to make the full normal

movement and will accordingly spring shaft 12. The springing of shaft 12 will cause a deflection of the fly wheel or belt pulley 13 which will in turn cause lug 22 to strike arm 29. Movement of arm 29 will actuate lever 36 to withdraw stop 41 from shoulder 42 whereupon spring 46 will automatically move slide 43 to throw the clutch shoe 28 and stop the press.

70 In order to provide for a fine regulation and adjustment of the spacing of the projection 33 on the arm 29 from the lug 22, the pivot pin 31 (Fig. 4) on which the arm 29 is mounted is eccentrically formed between its bearings. Angular adjustment of the pin will therefore regulate the spacing of the member 33 from the wheel 13, and incidentally the lug 22 carried thereby. Adjustment of the pin may be accomplished by a wrench or tool shaped to fit the squared head of said pin which is locked in the desired position by clamping bolts 47 adapted to compress the split bearings within which the pin is mounted.

75 The advantages and operation of the aforedescribed mechanism will be apparent without further description.

80 I am aware that many changes may be made without departing from the principles of this invention. I, therefore, do not wish 90 to be limited to the details shown or described.

I claim:

1. In a die press, the combination of a 100 rigid frame, a stationary die seated therein and a movable die reciprocable in said frame toward and from said stationary die, with means for stopping said press operable in accordance with the difference in movement of said movable die with respect to said frame and stationary die resulting from excessive resistance to the movement thereafter in one direction thereof caused by material of undue thickness between said die members.

105 2. In a die press, the combination of a rigid frame, a stationary die and a reciprocable die mounted therein and a drive shaft journaled in said frame for actuating said reciprocable die, with means operable by the springing of said shaft for stopping the 110 press when material of unusual thickness has been delivered between said die members.

115 3. In a die press, the combination of a rigid frame, a stationary die and a reciprocable die mounted therein, a drive shaft for operating said reciprocable die and a wheel on said shaft, with means actuated by said wheel for stopping the press when the die members encounter material of abnormal thickness.

120 4. In a die press, the combination of a rigid frame, a stationary die and a reciprocable die mounted therein, a drive shaft for operating said reciprocable die and a wheel on said shaft, with means for stopping the 130

press actuated by the deflection of said wheel from its normal plane of rotation caused by the die members encountering material of abnormal thickness.

5 5. In a die press, the combination of a rigid frame, a stationary die and a reciprocable die mounted therein, a drive shaft for operating said reciprocable die and a wheel on said shaft, with means for stopping the

10 press actuated by the deflection of said wheel from its normal plane of rotation caused by the die members encountering material of abnormal thickness, said means comprising a trip mechanism operable to disengage 15 the drive shaft from the source of power.

6. In a die press, the combination of a rigid frame, a stationary die and a reciprocable die mounted therein, a drive shaft for operating said reciprocable die with releas-

20 able mechanism carried by said shaft for stopping said press rendered operable by the springing of said shaft when the die members encounter excessive resistance to their relative movements.

25 7. The combination of a frame, a stationary die and a rotatable shaft carried thereby, a reciprocable die connected to said shaft for actuation thereby, and means rendered operable by deflection of said shaft induced 30 by excessive resistance to movement of said reciprocable die for causing cessation of rotation of said shaft.

8. The combination of a frame, a stationary die and a rotatable shaft carried by

35 said frame, a wheel on said shaft, a reciprocable die connected to said shaft for actuation thereby, and means rendered operable by deflection of said wheel from its normal plane of rotation induced through said shaft

40 by excessive resistance to movement of said reciprocable die for causing cessation of rotation of said shaft.

In witness of the foregoing I affix my signature.

45 WILLIAM CAMERON.
